Fig. 8

Fig. 11

Fig. 9

Fig. 12

FIG. 1 is a front perspective view of a combined wireless transmitter-receiver and recharger therefor, showing my new design;

FIG. 2 is a front perspective of the recharger unit, the transmitter-receiver having been omitted for clarity of illustration;

FIG. 3 is a front elevation of the transmitter-receiver;

FIG. 4 is a side elevation thereof;

FIG. 5 is a rear elevation thereof;

FIG. 6 is a top plan view thereof;

FIG. 7 is a bottom plan view thereof;

FIG. 8 is a front elevation of the unit in a separated position;

FIG. 9 is a side elevation of the recharger;

FIG. 10 is a rear elevation thereof;

FIG. 11 is a top plan view thereof; and

FIG. 12 is a front perspective view of the transmitter-receiver.

I claim:

The ornamental design for a combined wireless transmitter-receiver and recharger therefor, as shown.
